UNITED STATES PATENT OFFICE.

ANDREW L. GRENTZ, OF VAN NUYS, CALIFORNIA.

DESIGN FOR A LAMP SHADE.

Application filed May 5, 1922. Serial No. 2,101. Term of patent 3½ years.

To all whom it may concern:

Be it known that I, ANDREW L. GRENTZ, a citizen of the United States, residing at Van Nuys, in the county of Los Angeles and State of California, have invented a new, original, and ornamental Design for Lamp Shades, of which the following is a specification, reference being had to the accompanying drawing, forming a part thereof.

The figure is a perspective view of the lamp shade showing my design.

I claim:

The ornamental design for a lamp shade as shown.

ANDREW L. GRENTZ.
